UNITED STATES PATENT OFFICE.

EZRA L. ESTES, OF SHAWNEE, OKLAHOMA TERRITORY.

DESIGN FOR A RULE.

SPECIFICATION forming part of Design No. 34,924, dated August 13, 1901.

Application filed May 22, 1901. Serial No. 61,459. Term of patent 14 years.

To all whom it may concern:

Be it known that I, EZRA L. ESTES, a citizen of the United States, residing at Shawnee, in the county of Pottawatomie and Territory of Oklahoma, have invented and produced a new and original Design for a Metal Rule, of which the following is a specification.

This invention relates to a design for a rule, and the essential features of the same reside in the design as illustrated in the accompanying drawings, wherein—

Figure 1 is a perspective view of a rule embodying the features of the design. Fig. 2 is a transverse vertical section of the same.

The design is characterized by a body 1, having an intermediate longitudinally-extending flat member 2, with opposite side members 3, arranged at reverse oblique angles and of less length than the said member 2. The member 2 is continued from one end of the rule and has opposite parallel side

edges 4 and a rounded terminal 5, and the adjacent portions of the members 3 terminate in thin edges 6 at oblique angles to the member 2, the edges being at reverse angles to each other.

The flat member 2 is of the same width throughout its length, including the projected portion thereof beyond the terminals of the side members 3 at one end, and the angles of the edges 6 are oblique to the edges 4 or incline toward the rounded end 5.

Having thus described the invention, what is claimed as new is—

The design for a rule, herein shown and described.

In testimony that I claim the foregoing as my own I have hereto affixed my signature in the presence of two witnesses.

EZRA L. ESTES.
